UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

SAFETY HOIST MECHANISM FOR LOADING SKIPS.

Application filed February 10, 1923. Serial No. 618,369.

Street or road pavers of the class disclosed by my Letters Patent No. 1,141,470, issued June 1, 1915, are being constructed in extremely large sizes today as compared 5 with those manufactured at the time of my application for the above patent. To exemplify, the capacity of the mixing machines forming a part of said pavers is in many instances as much as thirty two cubic feet, 10 and the loading skip which feeds the batch of concrete aggregates to the mixer is called upon to raise huge loads from the ground and dump them into said mixer. These loads commonly exceed 6,500 pounds of aggregates, and the skips themselves are built 15 as large as twelve feet in width.

The problem of operating the loading skip in a large machine of the class referred to, is no mean one, having in view the factors 20 of safety and efficiency of movement. In other words the skip must be raised quickly, and must be brought to a stop at the extremes of its movements quickly, for most efficient action; and at the same time the 25 danger of falling of the skip accidentally thru breakage of any cables must be avoided.

I attain the objects above mentioned, and certain other objects that will be understood upon perusal of the following specification, by utilizing one or more of the following important provisions of construction:

In the first place, I employ a double hoisting cable running from a hoisting shaft to 35 the loading skip for elevating the latter in operation of the shaft. Since the skip handles tremendous loads affording it a tremendous leverage should it move even slightly laterally when lifting, there would be 40 liability of serious damage and improper operation if the lifting or hoisting cables for the skip do not act thereon with equal tension or pull while raising the skip and lowering it. This phase of action has created 45 the problem of supplying an equalizing device to act on said hoisting cables connected with the skip to equalize their tension for the purpose described. The method of arranging, and operating the cables, and 50 equalizing their tension when acting on the skip in raising or lowering movements of the latter, is consequently an important feature of this invention, and as presented hereinafter, it has proved in service of exceptional 55 advantage and practicability.

The double cable raising means for the skip has the additional function of affording safety in providing two different elevating contrivances, the failure of one of which would not result in accidental dropping of 60 the skip and consequent damage or loss of life.

In the machine of my invention, the skip hoisting cables themselves connect with an auxiliary hoisting shaft which is operated 65 from a main hoisting shaft somewhat after the manner which is presented in my Letters Patent No. 1,103,788, of July 14, 1914, and Letters Patent No. 1,107,171, of August 11, 1914, which illustrate machines of much 70 smaller construction than those now in use. From the auxiliary hoisting shaft which carries a large diameter cable drum, there leads a main hoisting cable to the main hoist shaft. Should this cable be broken ordinary, if no provision is made against the same, the skip will drop instantly with or without its load, according to the conditions. To provide against this, there is utilized a safety brake or device which enters into 75 combination in its action, with the control means for the auxiliary hoisting cables that connect with the skip direct, so that there are controls on the safety brake or device and the auxiliary hoisting cable mechanism 80 85 for the skip which are operable from a common control means.

Additionally, this invention includes certain contrivances which regulate the action of the main hoist shaft to brake its operation as the skip reaches its extremes of movement, thereby facilitating the proper acceleration of movement of the skip when necessary, for high efficiency of operation, and yet enabling the skip to be stopped quickly 95 without any tendency of the main hoist cable being caused to over-run on its drum, as would otherwise occur. The special brake devices employed for the last mentioned purpose likewise enter into peculiar combinative action with the general control mechanism.

The invention additionally involves an independent emergency control for the main hoist shaft, which in this instance forms a 100 part of the safety brake or control device, and is desirable in the operation of the machine.

Included in the invention are other specific features of construction, and for a full un- 110

derstanding of everything appertaining to the invention, reference is to be had to the following description, and accompanying drawings, in which;

5 Figure 1 is a partial side view of a machine embodying the invention, the supporting multiplanes or traction devices being omitted, as well as the distributing mechanism which forms no special part of the 10 invention.

Figure 2 is a horizontal sectional view of a large number of the parts shown in Fig. 1, especially the control devices which are intended to be illustrated primarily.

15 Figure 3 is a rear view showing certain of the mechanism illustrated in Fig. 1, as when looking from the rear end of the machine, the skip being omitted, but the hoisting cables being shown at least in part, as 20 well as a number of the control connections.

Figure 4 is a perspective view showing more particularly the selector mechanism utilized for controlling the action of the brakes affecting the operation of the main 25 hoist drum, the operation of the main skip hoist clutch, and certain other connected features of the mechanism.

Figure 5 is a side view partially broken away, of the safety brake and clutch means, 30 the safety brake being one which is automatic in its operation when its safety function comes into play, the auxiliary skip hoist shaft being shown in section.

Figure 6 is a vertical section view thru 35 the features of construction shown in Fig. 5.

Figure 7 is a diagrammatic plan view of the auxiliary hoist shaft, its cable drums, 40 guiding sheaves associated therewith, and the cables leading from the drums with the equalizing feature which embodies a construction applied to the under side of the skip, which skip is not illustrated.

Figure 8 is a slightly enlarged view showing 45 the method of training the skip raising cables about the guiding means on the skip and about the equalizer also carried by the skip.

Figure 9 is a fragmentary view of a portion 50 of the skip looking toward one of the cable guides, as when viewing the skip in side elevation.

Figure 10 is a view in elevation of one of 55 the cable guides carried by the skip, and the cables being shown in proper relation thereto.

Figure 11 is a rear edge view of the parts shown in Fig. 10.

Figure 12 is an end edge view of the parts shown in Fig. 10.

60 Figure 13 is a sectional view showing in plan the equalizer and method of training the cables thereabout.

Figure 14 is an edge view of the parts shown in Fig. 13.

65 Figure 15 is a perspective view showing

more particularly the brake devices co-operating with the main hoist shaft brake drum and hoist drum, with the controlling parts actuated from the skip in proper relations to other parts.

Fig. 16 is a somewhat diagrammatic, elevational view of the skip knock-out for the main hoist clutch.

General construction of machine.

The general construction of my machine will first be set forth.

A mixer A is mounted on the base frame B of the machine in any suitable manner, and as illustrated, the construction of my paving machine is that commonly known as the Koehring paver. The base frame B carries a superstructure frame C, in uprights of which is suitably journaled the auxiliary skip hoist shaft 1, seen best in Fig. 3. The shaft 1 carries the operating drum 2 of large diameter, and the skip hoisting drums 3 and 3^a of small diameters, the drums 3 and 3^a are provided, extending from their ends toward the central portions of their peripheries, with opposing spiral grooves, each groove adapted to have wound therein an end portion of a skip hoist cable, of which there are two designated 4 and 5. The skip hoist cables after being first wound at their ends a couple of times around the drums 3 and 3^a, lead over guiding sheaves 6, shown only in Fig. 7, same being carried by an upper extremity of the superstructure frame C, and from these downward beneath the skip 7 around which they are guided and connected by suitable members 8, and equalized by an equalizer lever 9 to be later set forth in detail. From the operating drum 2 upon the auxiliary shaft 1, there leads a main hoist cable 10 which is received by and winds about the main hoist drum 11 on the main hoist shaft 12, suitably journaled on the base frame B, and driven by a suitable motor carried on said frame in any well known manner. The same motor is adapted to drive the mixer A, and as seen somewhat generally in Fig. 2, there are driving connections which lead to the traction mechanism of the machine thru variable speed gearing.

While the mixer A is in operation, under the control of a main lever 13, a main hoist clutch 14 on the shaft 12 is adapted to operatively connect said shaft for driving the drum 11, which is otherwise loose thereon. This driving action is adapted to wind and unwind relatively to the drum, the main hoist cable 10. When wound on the drum 11 the cable 10 actuates the operating drum 2, and thereby the shaft 1, to raise the skip 7 thru the winding-up action of the cables 4 and 5, in relation to the drums 3. Unwinding of the cable 10 from the drum 11, causes a reverse operation which is obvious.

On the shaft 1 is the safety device which involves a safety brake and a safety clutch that will be more fully described hereinafter, in its proper place.

- 5 It is notable that as the skip 7 is raised, and when it assumes its upward extreme of elevation wherein it charges the mixer A, a knock-out device consisting of a yoke 15 connected with the pivot bracket 7^a of the 70
 10 skip 7, will have acted thru a rod 16 near the inclined brace 17 of the superstructure C, to release the clutch 14, and thereby discontinue the hoisting operation of the skip, at the same time applying a brake to hold 75
 15 the skip in its elevated position, as will later be set forth. The rod 16, as shown in Fig. 1, extends along the brace 17, passes thru an arm 18 on the shaft 19 which carries the clutch yoke 20 of said clutch 14. The lower 80
 20 end of the rod 16 has a head or abutment 16^a adapted to engage the arm 18 to shift it for rocking the shaft 19 to throw the clutch 14 out as the said skip 7 reaches its upward limit of movement. A spring 21 85
 25 tends to hold the arm 18 in a position maintaining the clutch yoke 20 and its clutch 14 disengaged, or with the driving action of the motor discontinued in relation to the main hoist drum 11.
 30 Without at present going into the detail construction of the safety or emergency brake, generally designated D in Fig. 3, and elsewhere in the drawings, it is notable that said device includes a brake drum 22 loose 90
 35 on the shaft 1, and about which a brake band 23 passes, the latter being applied continuously and automatically by means to be described, and also released from the drum 22 95
 40 by lever 13, or both applied and released, by the emergency lever 24 (see Figs. 1 and 3) located within easy reach of the operator. Normally there is a weighted lever 25 connected with said brake band 23 to hold the 100
 45 brake band in active relation to the drum to insure the continuous and automatic application of the brake 23 and thereby the safety function of the safety device. The weight on the lever 25 is designated 26.
 Under the above conditions it will be evident 105
 50 that assuming the main hoist drum 11 to be released from the clutch and free from the action of a local or immediately co-operating brake, the lowering of the skip 7 may ordinarily be controlled manually thru 110
 55 the brake band 23, operated by the lever 13 acting thru connections to the brake 23, drum 22 and parts clutching the latter to shaft 1, as hereinafter described. Likewise supposing the skip 7 to be elevated at any 115
 60 point in its travel, it may be held at such an elevation independently thru a downward movement of the emergency lever 24. In fact the skip may be locked against raising or the possibility of accidental lowering by 120
 65 turning a locking cam lever 27, pivoted to

one of the uprights of the superstructure C, said lever 27 being adapted to be thrown from the position of Fig. 1, leftward to engage its cam positively with the upper side of the lever 24 and stress lever 24 in the direction for applying brake band 23. 70

Thus far I have described the main features of my machine involving the mixer, the charging skip, the raising and lowering means for the latter, and the automatic knock-out device for the clutch that stops the skip at its upper limit of movement, which broadly are provisions already known in the art. Additionally, I have described that operation of the safety or emergency 80
 85 brake and clutch means that acts as an auxiliary manual control means for the lowering of the skip 7, and also as a brake to hold the skip raised at any desired elevation independently of the hoisting drum. 85

Double cable skip hoist means.

Referring again to the drums 3 and 3^a, and the cables 4 and 5, it is notable that the two cables 4 and 5 when extended from the drums into connection with the bottom portion of the skip 7, have a sort of U shaped arrangement in top plan. The two cables 4 and 5 have their ends winding about the drums 3 and 3^a from the bottom upwardly, so to speak, and in the same direction. Thus the cables wind upon the drums simultaneously and with a corresponding pull at both ends of each cable as it freely moves over the sheaves 6. The same phase of action reversely applies as the cables unwind from the drums. 95
 100
 105

It being almost a physical impossibility to so connect cables with drums as to maintain exactly the same tension on each cable if it be permanently connected between its ends with a part to be actuated thereby, and this problem being difficult when a single cable having a two end pull is used, it is obviously doubly difficult when two cables are connected to the same object and a two end pull for each cable is utilized. It is under the above conditions that I have availed of the equalizing arrangement of the cables, and the equalizing, guiding, and controlling devices illustrated in Figures 7 to 14 inclusive, and which will now be set forth. 110
 115

The guide members 8 each comprise a casting having tubular guide elements 8' and 8'', which viewed from above and at the innermost portion of the guide member, are in different vertical planes and the same horizontal plane, but which by reason of the peculiar curvature thereof in lateral directions, have their rear portions in the same vertical plane, but different horizontal planes. The equalizing member 9, see Figs. 13 and 14, is really a pivoted guide block having round end portions and pivoted on a short vertical axle 9^a fixed to the under side 125
 130

of the skip 7. The skip 7, as seen in Fig. 9, has an angle iron supporting flange or rest 28 on its under side which forms a clearance way in which the members 8 and 9 are 5 mounted by suitable attachment to said rest 28 and other flanged portions 7^a of the skip. In this clearance way at opposite sides of the skip are the end guide members 8 and at a middle point beneath the skip is located 10 the equalizing member 9. The cable 4 leads off from beneath the drum 3 over one of the sheaves 6, down thru the guideway 8' of the end guide member 8, to and thru a guide groove 9^x at the rear opposite portion of the 15 equalizer 9, and around a guide lug 9' of the equalizer, being thus crossed with the cable 5 adjacent thereto. Thence the cable 4 passes to and thru a guideway 8^x of the second end guide member 8, then to and thru 20 the guideway 8'' of said other opposite member 8, over the inside sheave 6 adjacent to the drum 3^a, and around and attached to said drum 3^a. The cable 5 leads from the 25 drum 3 over the inside sheave 6 adjacent to the drum 3, to and thru the guideways 8'' and 8^x of the guide member 8 in alinement with the drum 3 and sheaves 6 adjacent said drum. From the said guide member 8 the cable 5 leads to and thru the inner guide 30 groove 9^x of the equalizer 9, crosses the cable 4 and passes to and thru the other guideway 9' of the equalizer, thence to the guideway 8^x of the right hand guide member 8 of Fig. 7, to and thru the guideway 8' thereof, over 35 the outside sheave 6 nearer the drum 3^a, and around and attached to said drum 3^a.

With the above arrangement there is practically no movement of the cables 4 and 5 relative to the skip when the heaviest load is 40 upon the cables, namely when the skip is filled and being raised. Any slight variation in the tension of the cables becomes equalized as regards the pull of the cables transmitted to the skip, by rocking of the 45 member 9.

Control mechanism for skip operations.

Referring primarily to Figures 1 to 4 inclusive, it is notable that the main control lever 13 is connected by a rod 30 with one 50 arm of a bell crank lever 31. The other arm of the lever 31 is connected by a rod 32 leading to superposed selector arms 33 and 34 having curving or arcuate slots thereon. 55 The rod 32 has a T shaped head 32^a, the upper extension of which enters the slot of arm 33, and the lower extension of which enters the slot of the arm 34. The arm 34 is connected 60 with a vertical shaft 35 by being keyed or otherwise secured thereto, and the arm 33 is connected to move a sleeve 36 loose on the shaft 35 and having an arm 37. The arm 37 is connected by a rod 38 to a bell crank lever 39, see Fig. 3, and connected by a rod 40 to 65 the emergency or safety brake band 23.

The shaft 35 is equipped with an arm 41, see Figs. 1, 3, and 4. The arm 41 is connected by a rod 42 to an arm 43 which is rigid on the shaft 19 previously mentioned as having the clutch yoke that enables the 70 clutch 14 to be thrown in and out for communicating the drive from the motor to the main hoisting drum 11. The connections of the arm 34 and shaft 35 thru the rod 42 to the arm 43 on the shaft 19, are best seen in 75 Figs. 3 and 4, and Fig. 15.

There are two brake bands 45 and 45^a co-operative with a brake drum 45' on the hoisting drum shaft 12, connected with the hoisting drum 11. These brake bands 45 and 45^a 80 constitute braking devices to retard and brake the turning or rotation of the drum 11 as the skip 7 reaches the extreme of its upward movement, and also when it reaches the extreme of its lowering movement, 85 whereby to prevent overrunning action of said brake drum that would otherwise cause the cable 10 to overrun and become unduly slack, something to be avoided for obvious reasons. The operation of the brake bands 90 45 and 45^a is effected peculiarly under the control of the shaft 35 and the sleeve 36. Referring particularly to Fig. 15, it will be noted that when the shaft 35 is rocked to move the clutch arm 43, see Figs. 3 and 4, the 95 shaft 19 is of course rocked. Figure 15 shows that the brake bands 45 and 45^a have connected thereto, brake levers 54 pivoted at 55 to the frame work. The levers 54 automatically act to apply their brake bands 100 thru the provision of weights 54' on said levers. The operation of throwing in the clutch 14, by the arm 20 actuated by rocking of the arm 43, rocks the shaft 19 so as to cause an arm 44 thereon to act thru a connection 44' to rock upwards a cam 50 which engages beneath the free ends of the levers 54 whereby to raise said levers and their weights 54' in such a manner as to release the drum 45' from the brake bands 45 and 110 45^a. As previously described, when the skip 7 reaches its upper limit of movement, the parts 16 and arm 18 co-operate to disengage the clutch 14 by rocking movement of the shaft 19 reverse to that previously set forth, 115 such reverse rocking of the shaft 19 of course disengages the cam 50 from beneath the free ends of the levers 54, but it is to be noted that the skip 7 has connected to its pivot bracket 7^a a connection 70 composed of links and the small yoke 70^a which receives the free end portion of the outer brake band lever 54, and said lever is upheld while the skip is upraised so that its brake band 45 does not act upon the drum 45'. On the 120 other hand, however, disengagement of the cam 50 as just described, permits the other inner lever 54 to lower under the action of its weight 54', thereby applying the brake band 45^a to the drum 45', as the clutch 14 is 125 130

released by co-operation of the parts 16 and 18, the drum 45', and the cable winding drum 11 being thus braked to prevent overrunning of the cable.

5 Later on in the operation of the machine as the skip is lowered by movement of the rod 32 which actuates the sleeve 36, under the control of the lever 13, a second arm 46 carried by the sleeve near the arm 37, operates the rod 47 and a bell crank 48 to thereby lift a vertical lift bar 49, the upper end of which will engage the inner brake band lever 54 to raise it to free drum 45', while the skip is lowering under the control of the reverse movement of the lever 13. This action renders inactive the brake band 45^a which was rendered effective for braking the drum 45' when the skip reached its upper limit of movement. The inner brake band lever 54 is thus held elevated during lowering movement of the skip. Of course, as the skip lowers, the connection comprising the links 70 and yokes 70^a gradually moves downward until the outer lever 54 which co-operates with the brake band 45 is lowered sufficiently as the skip reaches the lower limit of its movement, to enable the brake band 45 to act on the drum 45'. In this way, and automatically, the skip causes a braking action on the drum 45', thru the brake band 45, to prevent overrunning of the cable 10 relatively to the drum 11, as the skip comes to a stop at its lower extreme of movement.

Summarizing this whole detailed action, 35 it is noted that on upward movement of the skip 7 on engaging the clutch 14, cam 50 is disengaged from the levers 54. The outer lever 54 is held up by the connection 70^a, the inner lever 54 is permitted to drop and activate its brake band 45^a to brake the movement of the drum 11. Then when the clutch 14 is thrown out and the skip 7 caused to lower, such action thru the lift bar 49 raises the previously active inner lever 54, rendering 45 inactive its brake band 45^a, and when the skip gets to its lower stopping position, the outer lever 54 will have moved downwardly sufficiently for the application of its brake band 45 to the drum 45'. In this way, in brief, do the levers and brake band co-operating with the drum 45', act to prevent overrunning of the cable 10 relatively to the drum 11.

The emergency brake or safety device.

55 This means D, best shown in Figs. 5 and 6, includes the described brake drum 22, with its coacting band 23, and certain internal contrivances. Drum 22 is loose on the shaft 1, and has an adjacent disk 60 that may be said to close the drum at one side. Disk 60 is keyed to the shaft 1 and carries a series of dogs 62 to engage notches 61 provided internally of the drum 22. The drum 22 has a hub extension 22^a on which are mounted the friction members 63 and 64, between which is the dog operating friction ring 65, having an arm 66. The arms 66 receive rods 67 each socketed at one end on a dog 62, and encircled by a spring 68. Bolt 70 head lugs 69 are provided for the ring 63 to fix the latter relative to the drum 22. The shaft 1 is rotated clockwise as the skip 7 is elevated to charge the mixer, and at the same time the drum 22 is held stationary 75 by its brake band 23, tho the disk 60 turns with the shaft 1, of course, carrying dogs 62 with it. As the drum 22 carries the rings 63, 64, and 65, and the last is connected to dogs 62, the turning of the disk 60 with the dogs is such that a pull is exerted on the dogs through parts 67 and 65, and the dogs stay free of the notches 61. If the cable 10 should break the disk 60 would reverse its above movement and the pull on the dogs 80 62 being relieved, they engage the notches 61, and since the drum 22 is held stationary by the band 23, the skip cannot fall.

The action of the dogs 62 to engage the drum 22 always takes place when the machine is operated to lower the skip. On this account, if the skip is to be lowered under control, the brake band 23 must be released from the drum 22, and this is done manually by the lever 13 usually, and in emergencies 95 the operation will be performed manually when desired by action of the manual lever 24 previously described.

So long as the lever 25 is lifted, as may be caused thru the connection 40, the skip 100 may lower under control, the weight 26 tho will restore the brake action of the band 23 instantly when necessary.

General operation of machine.

105 It will be assumed that the skip 7 is resting upon the ground, that the hoist clutch 14 is disengaged, and the control lever 13 is in the position of Fig. 1, namely at neutral. The lever 13 is thrown to the right in Fig. 1 for engaging the clutch 14 with the hoisting drum 11 to drive the latter to wind up the cable 10 thereon, turn the operating drum 2 clockwise with the drums 3 and 3^a, wind up the hoisting cables 4 and 5, and thus 110 raise the skip 7. While the skip is being raised, the drum 22 is stationary and the disk 60 is being turned clockwise, rotating within the drum 22, as previously set forth.

115 The action of the control mechanism for 120 the clutch 14 and the brake parts which coact with the drum 11, is substantially as follows: The movement of the lever to the right causes a movement of the rod 32, forcing the selector arm 34 clockwise with the shaft 35, see Figs. 3 and 4, and selector arm 33 remains quiescent. The movement of the arm 34 actuates the rod 42 and renders active or throws in the clutch 14 to start the turning of the hoisting drum 11 in the opera- 130

tion of lifting the skip above set forth. Simultaneously with the throwing of the clutch 14 into action, the rocking of the shaft 19 by which the clutch is moved, lifts the cam 50, see Fig. 3, which acts on and lifts the levers 54 that apply and release the brake bands 45 and 45^a. In this way the hoist shaft 12 and drum 11 are freed for rotation so that the cable 10 may wind freely thereon in the skip hoisting operation. As the skip rises to discharge its contents into the mixer, it actuates the yoke member 15, and as soon as the skip has reached the upper limit of its movement, the rod 16 will have been pulled to trip the arm 18 upwards, rocking the clutch shipper shaft 19 so as to throw out the clutch 14, whereupon the skip stops and is held from moving downwards by means of the brake band 23 acting on the shaft 1 thru the drum 22, the dogs 62, and the disk 60 keyed to the shaft 1. Also as the skip reaches its uppermost position, the brake band 45^a is applied to the drum 45' on the main hoist shaft 12, to thereby brake the turning of the drum 11, arresting movement of the latter and preventing any tendency of said drum to continue movement thru its inertia of previous operation. The result of such undesired turning movement would be to unwind the cable 10 unduly, creating slack that would interfere with the efficient operation of the machine. When it is desired to lower the skip, the control lever 13 is moved to the left across its neutral point or reversely to the direction previously mentioned, and this imparts an opposite movement which causes lowering of the skip, the leftward movement of the lever 13 actuating the selector arm 33 this time and the sleeve 36. The rod 38 is thus operated, and its movement is transmitted to the lever 25 and other parts at the upper portion of Fig. 1, which control the release of the brake band 23 from the drum 22. The rod 38 of course actuates the rod 40 and arm 40^a to the above end, and the release of the tension of the safety brake band 23 obviously permits the drum 22 to turn in a counterclockwise direction, actuated by the dogs 62 and the disk 60, under the influence of the pulls of the cables 4 and 5 which are then unwinding from the drums 3 and 3^a in the skip lowering movement. The skip can be instantly stopped at any point in such lowering movement. The action of the selector arm 33 and other parts just described, under influence of the leftward movement of the lever 13, not only releases the brake band 23, but also operates the crank 48 thru the rod 47, and thereby raises the lifting member or rod 49 so as to release the brake band 45^a acting on the drum 45', removing the braking action of this member from the drum 45', and permitting the hoisting drum 11 to turn incident to the unwinding of the cable 10 there-

from. As the skip goes down the linkage 70 will automatically lower, gradually causing application of the brake band 45 to the drum 45', and thereby to the drum 11, so that as the skip reaches its lower limit of movement the drum 11 will again be braked, so to speak, and prevented from overrunning by reason of the inertia of its cable unwinding movement, causing the cable to unwind more than necessary. 75

It will be noted on reference to Fig. 4, that the arm 34 is provided with a hook member 34^a and that the rod 32 has a hook 32''. The purpose of these provisions is as follows: In the event it is desired to stop the skip 7 in its upward travel before the regular knockout action caused by the rod 16 acting on the arm 18, the operator may throw the lever to the left, or in other words restore it to its central neutral position. This will cause the hook 32'' to engage the hook member 34^a and throw the arm 34 into its normal or original position. This will cause a release action of the clutch 14. Simultaneously, of course, the safety brake 23 will hold the skip elevated and subject to further raising movement if the lever 13 is again thrown to the right, or subject to be lowered under the control of either the lever 13 thrown to the left of its neutral position, or the lever 24 which always gives immediate manual control. 90

Also in the above action cam 50 will lower allowing brakes 45 and 45^a to stop the cable from further unwinding. 100

What I claim is:

1. In concrete mixer loading mechanism of the class described, in combination, a loading skip, hoisting means therefor including a plurality of cables independently connected with the skip, and means for operating both cables with equalized forces for elevating the skip including cable equalizing devices on the skip. 105

2. In loading mechanism of the class described, in combination, a loading skip, hoisting means therefor including a plurality of cables independently connected with the skip, so that if one cable breaks the other will hold, winding means for the cables to act thereon simultaneously to raise and lower the skip, and an equalizing device carried by the skip and common to both cables to equalize their action on the skip in actuation of the latter. 110

3. In loading mechanism, the combination of a loading skip, hoisting means therefor including separate cables extending downward to one side of the skip, across the skip, and upward at its other side, and connected with the skip so that in the event of breakage of one cable the other cable will hold, a winding mechanism common to both cables for actuation thereof, and an equalizing member on the skip cooperative with 115

both cables for equalizing the forces transmitted to the skip through the cables from the winding mechanism.

4. In loading mechanism of the class described; the combination of a loading receptacle adapted to be raised and lowered, cable hoisting means therefore including separate cables having relatively movable connection with and extending transversely beneath the skip, means for actuating the cables, and means for equalizing the effective forces transmitted to the skip from said cables.

5. In loading mechanism, the combination of a skip; hoisting means for the skip including a hoisting shaft, winding drums upon said shaft, a pair of cables adapted simultaneously to wind on and unwind from said drums and having engagement with the skip, and an equalizing device on the skip engaging the cables whereby equal operating forces of both cables may at the same time be transmitted to the skip, the cables extending crosswise of the skip beneath the same and leading to the winding drums from opposite sides of the skip.

6. In loading mechanism, the combination of a skip, hoisting means for the skip including a hoisting shaft, winding drums upon said shaft, a pair of cables adapted to wind on and unwind from said drums and having engagement with the skip, whereby equal operating forces of both cables may at the same time be transmitted to the skip, the said cables being arranged in substantially parallel relations as regards the elements thereof, said cables extending downwardly from one drum beneath the skip and then up to the other drum, and an equalizing device intermediate and common to the cables.

7. In loading mechanism of the class described, the combination of a skip, hoisting means therefor including a pair of cables, a hoisting shaft, drums on said hoisting shaft, each drum having the ends of said cables winding thereabout and each cable winding from an end of the drum toward its middle portion, the cables intermediate their ends being engaged with the skip, a rocking equalizing member pivoted to the skip and having the cables engaging the same from opposite sides thereof, and guiding means on the skip for controlling the engagement of the cables therewith.

8. In loading mechanism of the class described, the combination of a skip, pivoted at one end, hoisting means therefor for raising its other end including a pair of cables, a hoisting shaft, drums on said hoisting shaft, each drum having the ends of said cables winding so as to wrap thereabout in opposite directions namely, from the drum ends toward its middle, the cables intermediate their ends passing beneath the skip, a

rocking equalizing member pivoted to the skip and having the cables engaging the same from opposite sides thereof, and guiding means on the skip for controlling the engagement of the cables therewith, said 70 rocking member and guiding means so co-acting with the cables as to permit relative slippage of the same and the skip.

9. In loading mechanism of the class described, the combination of a skip, hoisting 75 means therefor including a pair of cables, a hoisting shaft, drums on said hoisting shaft, each drum having the ends of said cables winding thereabout, the cables intermediate their ends being engaged with the 80 skip, a rocking equalizing member pivoted to the skip and having the cables engaging the same from opposite sides thereof, and guiding means on the skip for controlling the engagement of the cables therewith. 85

10. In a machine of the class described, the combination of a loading skip, means for raising said skip including a main hoisting drum, an auxiliary hoisting shaft, an operating drum on the auxiliary shaft, cable 90 means connecting the latter to the skip, other cable means connecting the operating drum with the main hoisting drum, control means for the main hoisting drum to clutch same to a driving element to raise the skip 95 and unclutch it to stop the skip raising movement, brake means coacting with the auxiliary shaft in lowering the skip or holding it raised, and other brake means to coact with the main hoisting drum to apply 100 brake forces thereto when the skip is stopped at its upper limit of movement, and stopped at its lower limit of movement.

11. In a machine of the class described, the combination of a loading skip, a main hoisting shaft and hoisting drum operated thereby, an auxiliary hoisting shaft, cable means connecting said auxiliary shaft with the main hoisting drum, auxiliary hoisting cable means connecting the auxiliary shaft and the skip, main control means for driving the hoisting drum from the drive shaft, brake means to coact with the auxiliary shaft and releasable to permit it to lower the skip, and automatic safety clutch means coacting with the auxiliary shaft to prevent dropping of the skip if the cable means between the hoist shafts breaks while said brake means is released during upward or lowering movements of the skip. 115 120

12. In a machine of the class described, the combination of a loading skip, a main hoisting shaft and hoisting drum operated thereby, an auxiliary hoisting shaft, cable means connecting said auxiliary shaft with the main hoisting drum, auxiliary hoisting cable means connecting the auxiliary shaft and the skip, main control means for initiating driving of the hoisting drum from the drive shaft, safety control means for 125 130

5 preventing lowering of the skip in the event of breakage of the cable connection between the hoisting drum and auxiliary hoisting shaft, and operative connections between the safety control means and the main operating means whereby the former may be controlled from the latter.

10 13. In a machine of the class described, the combination of a loading skip, a main hoisting shaft and hoisting drum operated thereby, an auxiliary hoisting shaft, cable means connecting said auxiliary shaft with the main hoisting drum, auxiliary hoisting cable means connecting the auxiliary shaft 15 and the skip, main control means for driv-

ing the hoisting drum from the drive shaft, safety control means for preventing lowering of the skip in the event of breakage of the cable connection between the hoisting drum and auxiliary hoisting shaft, the auxiliary cable means including a pair of cables between the auxiliary shaft and the skip, with means to create equalization of the lifting effects thereof on the skip, so that if either cable breaks the other will be effective to prevent dropping of the skip and for temporary use to operate the skip.

20 25 In testimony whereof I affix my signature.

ERICH H. LICHTENBERG.
